UNITED STATES PATENT OFFICE.

ROBERT L. FRINK, OF CLEVELAND, OHIO.

REGULATION OF AIR-SUPPLY IN DRAWING GLASS CYLINDERS.

972,614.

Specification of Letters Patent. Patented Oct. 11, 1910.

Application filed November 27, 1908. Serial No. 464,654.

To all whom it may concern:

Be it known that I, ROBERT L. FRINK, a citizen of the United States, and a resident of Cleveland, county of Cuyahoga and State of Ohio, have invented a new and useful Improvement in Regulation of Air-Supply in Drawing Glass Cylinders, of which the following is a specification, the principle of the invention being herein explained and the best mode in which I have contemplated applying that principle, so as to distinguish it from other inventions.

It need scarcely be pointed out that the supplying of air to the cylinder in the drawing of glass by mechanical means calls for considerable delicacy of adjustment, inasmuch as such mechanical supply takes the place of that supplied from the lungs of the blower and controlled by his skill and experience, in the art as manually practiced. While this difficulty of maintaining a proper rate of supply is apparent even in the continuous process of drawing cylinders where the air is supplied to a portion of the cylinder lying between a fixed head rising from the bath of molten metal and the level of such metal itself, such difficulty is considerably increased where the discontinuous or intermittent method of drawing prevails, since a gradually increasing amount of air is required in order to properly distend the cylinder walls. In the latter connection, indeed, there have been some attempts for effecting a variation in the rate of supply, such variation being correlated by mechanical means with the movement of the bait, or carriage whereby such bait is raised and lowered. By the present invention, on the contrary, I propose to effect this regulation in a more subtle and satisfactory fashion, by making the rate of supply dependent upon the pressure obtaining from time to time within the cylinder itself, and it is further proposed that such invention shall be equally applicable to either of the processes or methods of drawing cylinders referred to above.

To the accomplishment of these and related ends, said invention, then, consists of the steps and means hereinafter fully described and particularly pointed out in the claims. Prefatory to such description, I should explain that the pressure actually existing within the cylinder is affected not merely by the rate at which fluid is supplied thereto, but is dependent upon various

conditions. Thus the composition of the molten glass, affecting as it does the viscosity of the latter; the temperature of such glass, which likewise affects its viscosity; the size of the cylinder, determining the volume of air that is heated and thereby the amount of expansion; the speed of the draw, which determines the area of heated, semi-plastic glass that is exposed to the action of such air; the initial temperature of the entering air; and the specific heat of such air, whereby air is generically designated any suitable pressure fluid, and specifically the mixture of various gases constituting the atmosphere, including watery vapor in varying amount; all these coöperate in governing the pressure within the cylinder. However, these different influences can all be more or less accurately determined, and, once determined, for any particular batch of glass and period of time, a suitable control of the volume of air simultaneously supplied to the cylinder will succeed in regulating the diameter and other characteristics of the latter to a degree of certainty thus far unattained in glass drawing operations. It has been already explained that it is with the control of such air volume that the present invention is concerned; the determination and control of the other influences enumerated above are properly subject matters for independent explanation and disclosure.

The annexed drawings and the following description set forth in detail certain means and one mode of carrying out the invention such disclosed means and mode illustrating, however, but one of various ways in which the principle of the invention may be used.

In said annexed drawings:—Figure 1 is a partial side elevation and partial section of a continuous cylinder drawing plant, wherein have been incorporated my several improvements for regulating the supply of air to the cylinder being drawn; Fig. 2 is a similar view of a discontinuous or intermittent drawing apparatus, showing the mode of incorporating such improvements therein; while Figs. 3, 4 and 5 are sectional views of various details of such improved apparatus.

Referring first of all to the continuous type of drawing mechanism illustrated in Fig. 1, it should be stated that the general arrangement and mode of operation thereof is fully set forth in my issued Patent No. 846,102, bearing date March 5, 1907. For

the present purpose it will hence suffice to state that the cylinder is designed to be drawn from a drawing pot, or receptacle B to which the molten glass is supplied from an adjacent glass melting furnace (not shown) by means of a passage or conduit A, a suitable gate being interposed in such passage, whereby the flow of molten glass may be stopped when desired. The drawing mechanism proper comprises a set of rolls D, shown as being two in number in the case in hand, and located directly above the drawing pot B just described. The cylinder or "roller" being drawn is pressed 10 between these rolls D, and drawn upwardly by them once it has been started. Rising upwardly through an opening in the bottom of the drawing pot, or receptacle, to a short distance above the contemplated level of 15 molten glass therein, is a drawing head B', around which the cylinder is drawn, and by means of which, taken in conjunction with an air supply that is furnished through said head, the diameter of such cylinder is regulated.

In its details of construction, drawing head B' may take on various forms, the one here shown, as also the specific construction of pot B forming no part of the present 20 invention. In the present instance, such head is conical or funnel like in shape, and is supported upon two concentric pipes b⁵ b⁶, which together with such head are constructed of suitable material to resist the 25 temperature to which they are exposed when surrounded by the metal in pot B. The central aperture b⁷ in the head is connected as shown with the inner b⁸ of the two pipes constituting support, while in the base of 30 the head there is formed an annular chamber b⁹ surrounding such central aperture and provided with lateral ports b⁹, such chamber having communication with the outermost b⁵ of the two supporting pipes. Air 35 under pressure is designed to be supplied to the head through the outer pipe b⁵, and thence through the chamber b⁹ and ports b⁹ to the portion of the cylinder lying between the head and the level of the metal in the 40 pot. At the same time, if desired, suction 45 means may be connected with the inner pipe b⁸, although this is a matter of indifference in the present connection, it being to the regulation of the supply of air through such 50 outer pipe that attention will here be directed.

For supplying air to the pipe in question, suitable mechanism is provided, such mechanism comprising a supply pipe c', a drum 55 c² laterally connected with such supply pipe, and a blower C' having its delivery pipe c³ extending through said drum, and opening laterally into the same. Weighted escape valves c⁴ c⁵ are provided for the upper end 60 of the blower delivery pipe, and for an open-

ing c⁶ in said drum located in its side, substantially opposite the supply pipe, (see Fig. 3): The general details of the air supply mechanism thus far described, likewise are not presented as a part of the present invention, being fully set up and claimed in my co-pending application, filed July 24, 1908, Serial No. 445,077. By such mechanism, I am enabled to supply a substantially constant volume of air to the portion of the 70 glass cylinder under consideration, such volume being dependent only upon the aperture of supply pipe c'. In the apparatus as previously described, I show simply a manually operable diaphragm or other valve for 80 adjusting such aperture, it being then contemplated that no further regulation in this particular would be required, once the apparatus is in operation. To render this air supply mechanism, however, still more delicately responsive to the condition of distension of the plastic base of the "roller" I now substitute for such manually controlled valve, a valve automatically operated by manometric means connected with a pipe 85 leading to the cylinder portion to which the air is being supplied. In the preferred form illustrated, (see Fig. 5), such means comprise an open vessel D containing a suitable liquid, a plate d pivotally mounted on pins d' forming a transverse axis above said vessel, and a second vessel d² inverted within said first vessel, and inclosing the end of a duct d³ that passes upwardly through pipes b⁵ b⁶ forming the support of the drawing 90 head B, and opens into the lower cylinder portion, as has been already indicated. This duct rises safely above the level of the liquid in the outer vessel D of the manometer, and, as will be obvious, variation of pressure in 95 such cylinder portion will by reason of the connection thus had cause the inverted vessel of the manometer d² to rise and fall responsively. The one end of the pivotally mounted plate connected with such rising 100 and falling vessel, is provided with a counter-weight, d⁴, and the other is connected with the valve in supply pipe c', by means of a connecting rod or link d⁵. This 105 valve is preferably of the liquid-seal type, 110 in order that its operation may be as frictionless as possible, not only because an undue burden would otherwise be imposed upon the manometer, constituting the operative means for said valve, but also because 115 the pressures dealt with, as will be readily understood, are relatively low.

By referring to Fig. 4, such valve will be seen to comprise an outer casing D' containing liquid, as for instance glycerin, above 120 which extends the portion of pipe c' leading from drum c². Over the end of such pipe is inverted an inner, vertically movable casing d⁶ connected with the manometer as has been described, which inner casing has its 125

lateral walls perforated as shown, so that the effect of its rising and falling will be to vary the amount of air passing therethrough. It will thus be seen that any variation in pressure in the lower portion of the cylinder or "roller" will be promptly and wholly automatically effective to vary the rate of supply of air thereto, so that such pressure will be maintained substantially constant.

Referring now to the adaptation of my improved regulating apparatus to the discontinuous, or intermittent, drawing mechanism as shown in Fig. 2, the detailed construction of the air supply mechanism proper and the manometric controlling means need not be specifically noted, since such construction corresponds exactly with that just described, and similar reference letters have been applied thereto. Instead, however, of connecting the air supply pipe c' with a head B' rising above the level of the metal in the pot, such air supply pipe is connected with the closed bait E that here constitutes, in conjunction with suitable operating mechanism, the drawing means proper. Such air-supply pipe, in effect, comprises a series of telescoping pipes, $e' e^2 e^3$, with the upper of which pipe c' , of the air supply mechanism is connected. In the absence of any drawing head B' , furthermore, the duct d' for the manometer rises upwardly from the bottom of the drawing pot, projecting a sufficient distance above the level of the metal therein to assure its remaining unobstructed. The portion of the duct thus within the pot must, of course, consist of suitable heat resisting material. Not only is my improved method of regulation thus adaptable, as shown, to diverse types of glass drawing mechanism, but the simplicity of the construction and operation of the apparatus involved, relieve such method of difficulties usually to be apprehended in connection with automatic devices.

In conclusion it may be remarked that since the pressure of air within the cylinder, and, consequently, the distention of the plastic portion of such cylinder are functions of various influences, so one or more of these might be selected as the factor controlling the rate of supply of air, instead of such pressure, which is rather to be regarded as a resultant of them all.

Other modes of applying the principle of my invention may be employed instead of the one explained, change being made as regards the means and the steps herein disclosed, provided those stated by any one of the following claims or their equivalents be employed.

I therefore particularly point out and distinctly claim as my invention:

1. The method of producing hollow glass articles, which consists in drawing a cylin-

der from a bath of molten glass, causing a flow of pressure fluid to said cylinder and utilizing pressure within the cylinder independently of the pressure supply to the cylinder for regulating said pressure supply.

2. In apparatus for drawing glass a receptacle for the molten glass, mechanism for drawing the cylinder, means for effecting a flow of pressure fluid to the interior of the cylinder, and means having independent communication with the interior of said cylinder and actuated by variations in pressure therein for controlling the air supply.

3. In apparatus for drawing glass, a receptacle for the molten glass, mechanism for drawing the cylinder, means for supplying fluid pressure to the interior of such cylinder, and manometric means having independent communication with the interior of the cylinder whereby it will be operated by changes of pressure within the cylinder for controlling the fluid pressure supply.

4. In apparatus for drawing glass, a drawing pot or receptacle mechanism co-operative with said receptacle to draw a cylinder from molten glass therein, means for supplying fluid pressure to the interior of such cylinder, a valve controlling such supply and a manometer adapted to operate said valves, said manometer having independent pipe connection with the interior of said cylinder so as to be operated by changes of pressures within the latter.

5. In apparatus for drawing glass, a drawing pot or receptacle, mechanism co-operative with said receptacle to draw a cylinder from molten glass therein, a head around which such cylinder is drawn, an air supply pipe in connection with said head opening into the portion of said cylinder between said head and the bath, a manometer and a second pipe opening into such cylinder portion and connected with said manometer.

6. In apparatus for drawing glass, a drawing pot or receptacle, mechanism co-operative with said receptacle to draw a cylinder from molten glass therein, a head around which such cylinder is drawn, two pipes, one within the other, for supporting said head and opening, the one into the portion of said cylinder between said head and the bath, and the other into the portion of said cylinder above said head, means adapted to withdraw air from said cylinder through such last-named pipe and supply air through the first named pipe, a manometer adapted to operate said valve, and a second pipe opening into such portion between said head and the bath and connected with said manometer.

7. Method of producing hollow glass articles, which consists in drawing the article from a bath of molten glass, causing the flow of pressure fluid into the article, and

governing such flow by means of the pressure within said cylinder through a direct and unrestricted means to a pressure regulating device.

5. 8. In an apparatus for drawing glass, a receptacle containing the molten glass, mechanism coöperative with the said receptacle for forming a hollow article; an air supply pipe in connection with said receptacle and said mechanism whereby the flow of pressure fluid may be introduced into the article, manometric means for controlling the flow of the pressure fluid, and direct and unrestricted independent means for connecting the space within the article with the manometric means.

9. A method of producing hollow glass articles, which consists in drawing a cylinder from a bath of molten glass, causing the flow of pressure fluid to the interior of such cylinder, and utilizing the pressure created within said cylinder to control the fluid supply.

10. A method of producing hollow glass articles, which consists in drawing a cylinder

from a bath of molten glass, causing the flow of pressure fluid to the interior of such cylinder, and utilizing pressure created in said cylinder to control manometric means operatively associated with controlling means 30 for pressure to said cylinder.

11. An apparatus for drawing glass, a drawing pot or receptacle, mechanism operating with such receptacle to draw a cylinder from molten glass therein, fluid pressure generating means, supply pipes connecting such cylinder with the fluid pressure generator, primary pressure regulating means in connection with said supply pipe, and fluid regulating means connecting said supply 40 pipe with said cylinder, operated by the pressure within said cylinder through independent connecting means.

Signed by me this 17 day of November, 1908.

ROBERT L. FRINK.
